COMPARTMENT CAN FOR PACKAGING FOODS

Edward Holoubek, Roy, Mont.

Application September 1, 1934, Serial No. 742,502

1 Claim. (Cl. 220—20)

This invention relates to certain new and useful improvements in compartment cans for packaging foods.

The primary object of the invention is to provide a compartment can for the packaging of foods wherein different foods may be assembled in a compartment can to constitute a complete dinner or meal and if desired, the can and its contents may be heated and a hot meal served when the can is opened.

A further object of the invention is to provide a compartment can of the foregoing character having partitions therein to form the compartments that are non-communicative with a side of the can flattened in the lengthwise direction thereof and weakened at the parallel edges of the flattened portion whereby the latter may be severed from the can body by a suitable key to successively expose the compartments of the can for access to the compartments.

A further object of the invention is to provide a compartment can wherein the several compartments are retained in assembled relation by a sealing or tie wire or the like and separable at the partitions thereof to permit access to each compartment.

A still further object of the invention is to provide a compartment can for packaging foods wherein partitions in the can to form the compartments extend into annular seam portions at adjacent ends of the compartment with the seam portions bent into L-formation so that the can may be annularly severed adjacent a seam to obtain access to a selected compartment.

With the above and other objects in view that will become apparent as the nature of the invention is better understood, the same consists in the novel form, combination and arrangement of parts hereinafter more fully described, shown in the accompanying drawings and claimed.

In the drawings:—

Figure 1 is a perspective view of a compartment can for packaging foods constructed in accordance with the present invention, showing a flattened side partially opened and exposing a compartment of the can;

Figure 2 is a detail sectional view, in perspective, showing the engagement of the marginal edge of a partition with the can wall;

Figure 3 is an enlarged detail sectional view showing the sealed engagement between a partition and can wall;

Figure 4 is a perspective view of another form of compartment can wherein the several separable sections or compartments of the can are retained

in assembled can formation by tie wires or the like;

Figure 5 is a fragmentary perspective view, in section, showing the tie wire for the can sections or compartments and the seams are joined between the sections or compartments of the can;

Figure 6 is a detail sectional view showing a partition, sealing gasket and adjacent edges of two can compartments, all in spaced relation;

Figure 7 is a detail sectional view, similar to Figure 6, showing the parts in sealing engagement with each other;

Figure 8 is a perspective view of a compartment can with a joint or seam between adjacent sections that is L-shaped in formation;

Figure 9 fragmentarily illustrates in perspective and section a partition and adjacent end of a can section with the mating flanges on the partition and can;

Figure 10 is a fragmentary side elevational view, partly in section of the can shown in Figure 8, illustrating the steps of assembling the partition and can flanges to form the seam between the compartments;

Figure 11 is an enlarged detail sectional view of the can seam in its initially assembled relation;

Figure 12 is an enlarged detail sectional view, similar to Figure 11 with the partition and can flanges partially compressed together;

Figure 13 is an enlarged detail sectional view, similar to Figures 11 and 12 showing the completed seams between the sections or compartments of the can;

Figure 14 is a fragmentary perspective view in section of another form of partition and can seam between each compartment;

Figure 15 is a fragmentary perspective view of the partition shown in Figure 14;

Figure 16 is a detail sectional view showing the sealed or soldered connection between the sections of the can and partition of Figure 14;

Figure 17 is a detail sectional view of another form of can seam between the compartments with a partition at the seam and illustrating the initial assembly of the parts;

Figure 18 is a detail sectional view, similar to Figure 17 of the seam shown in Figure 17 with the seam of L-formation with the partition clamped at its marginal edge between flanges on the can sections;

Figure 19 is a detail sectional view of another form of can seam with partitions in its initial assembly relation;

Figure 20 is a detail sectional view showing the

can section flanges compressed into engagement with the marginal edge of the partition;

Figure 21 is a detail sectional view of the completed L-shaped seam and illustrating one flange 5 of a can section engaged with the partition at one side and extended to be positioned between the partition and other can section flange;

Figure 22 is a side elevational view, partly in section of another form of compartment can, the 10 upper seam indicating the initial assembly and the lower seam indicating the complete assembly with the seam of L-formation;

Figure 23 is a sectional view of the partition of 15 Figure 22 in its initial position; and

Figure 24 is a sectional view of the partition 20 shown in Figure 22 in its completed extended form, but detached from the can.

In each of the several forms of the invention disclosed herein, the can is either of the 25 sectional type with partitions anchored at their marginal edges in the seams between the sections or the partitions are anchored in the can so that the compartments formed thereby are non-communicative so that foods of different kinds may be 30 placed in the desired compartment to comprise, if desired, a complete dinner or meal. The entire can may be heated before opening for the serving of a hot meal, or access may be obtained to the desired compartment and an important 35 feature of the sectional can is the L-shaped seam between the compartment which lends itself to an appropriate opening device for access to the desired compartment, the other compartments remaining hermetically sealed.

Referring more in detail to the accompanying drawings, and particularly to Figures 1 to 3, there is illustrated a compartment can for packaging foods which comprises a cylindrical body wall 25 provided with closed end walls 26 and 27 with diametrically opposite sides of the cylindrical wall 25 flattened in longitudinal directions as at 28, the marginal edges of the flattened section 28 having weakened opening or tear lines 29. One side flat portion 28 of the can is extended over the top 26 40 in the form of a tongue 30 shown by dotted lines for attachment to an opening key 31 while the flattened portion 28 at the opposite side of the can carries a tongue extension 30a that extends over the bottom wall 27 of the can as shown by dotted lines in Figure 1. With this arrangement, either end compartment of the can 25 may be 45 opened and intermediate compartment or compartments remained in a hermetically sealed condition. Access may be had to all of the compartments by the opening of one of the flattened sides 50 28 for the entire length of the can 25.

A series of plate or disk partitions 32 are placed in the can 25 in the order of filling the can with food and the marginal edges of the partitions 32 are sealed to the inner face of the can wall 25 to 55 exclude communication between the several compartments of the can. As shown more clearly in Figures 2 and 3, an annular channel member 33 opening at the outer side and integral with the partition 32 carries a compressible gasket 34 in the channel portion thereof that has intimate contact with the inner face of the can body 25, this channel member and gasket being moved downwardly over the inner wall of the can with the partition 32 as illustrated. To obtain access 60 to the can, the key 31 engaged with the tongue 30 of the flattened side wall section 28 is rolled to roll the flattened side wall section thereon and tear the same from the can body at the weakened lines 29, the roller portion of the can being illus-

trated at 35 in Figure 1, with all three compartments of the can exposed.

In the form of compartment can illustrated in Figures 4 to 7, the can is formed of separable sections sealed together at their joints or seams by packing elements with the several sections maintained in assembled can formation by means of a tie wire or the like that may be soldered or otherwise anchored in position. While the can in this form of the invention and in other forms disclosed herein is illustrated as being of the three-sectional type, it is to be understood that the can may embody as many sections or compartments as desired. The can 36 is illustrated as comprising an intermediate section 37 and end sections 38, the latter being provided with outer end walls 39. The joint or fitting between adjacent ends of the sections 37 and 38 is shown more clearly in Figs. 5 to 7. The compartment can 36 is of cylindrical formation and the lower edge 20 of the upper section 38 carries an inwardly directed annular flange 40. A partition 41 has an upstanding annular wall 42 adjacent its peripheral edge with the upper end of the annular wall flanged outwardly in a horizontal plane as at 43 to rest upon the inwardly directed flange 40 upon the end section 38 and the outer edge of the flange 43 is shouldered upwardly as at 44 for contacting the inner face of the can section 38. The upper edge of the intermediate section 37 30 of the can carries an inwardly directed annular flange 45 shouldered upwardly at its inner edge as at 46 and these elements in their steps of assembly are illustrated in Figs. 5 and 6. A sealing gasket 47 of ring formation is interposed between 35 the flanges 40 and 45 of the can sections 38 and 37 respectively and when the two can sections are moved toward each other as shown in Figure 7, the sealing gasket 47 is pressed and moved into intimate contact with the wall flanges 40 and 45 as well as the upstanding wall 42 upon the partition 41 and the shouldered portion 46 upon the flange 45 that bites into the sealing gasket as shown in Figure 7. The connection between the lower edge of the intermediate section 37 and 45 the upper edge of the lower section 38 is identical with the connection or seam shown in Figures 6 and 7 and it will be observed that the compartments formed by the partitions 41 are entirely non-communicative so that different kinds 50 of foods may be placed in the desired compartments. With the can sections 37 and 38 assembled, as described, they are held in such position by a tie wire comprising a base portion 48 underlying the lower end of the can 36 and upstanding side legs 49 that are bent inwardly at their upper ends as at 50 to overlie the upper end 39 of the can, the tie wire being soldered or otherwise secured to the assembled can section. To obtain access to the compartments of the sections 37 and 38, it is only necessary to remove the tie wire from the can and the sections may be readily removed, the interfitting engagement of the upper partition 41 with the lower edge of the can section 38 providing a bottom wall 65 for said upper can section and the lower partition 41 provides a bottom wall for the intermediate can section 37.

In the form of the invention shown in Figures 8 to 13, the can 51 is formed of three sections 52 joined together at their adjacent ends by a seam in which the marginal edge of a partition is embedded, the outer end sections having closed end walls 53. The adjacent ends of the can sections 52 are provided with outwardly directed annular 75

flanges that are of zig-zag or double V-formation in cross-section as shown at 54 in Figures 9 to 12 and the partition 55 interposed between adjacent ends of two sections is provided with a similarly formed annular flange 56 that has mating engagement with the two flanges 54. Figure 9 illustrates a can section end and an associated partition, while Figure 10 illustrates the can with a completely sealed or soldered seam and another seam in the process of formation. In the enlarged detail sectional view of Figure 11, the mating zig-zag flanges of the can section ends 52 and the associated partition 55 are illustrated in the initial step of assembly, while Figure 12, shows the flanges partly compressed to be finally moved into a unitary flange structure of L-formation as shown at 57 in Figures 8, 10 and 13 with the marginal edge of the partition sealed in the soldered seam 57. An appropriate construction of can opener may be employed and move over the L-shaped seam 57 as a guide for severing one section or compartment of the can from the rest of the can and access to the several compartments of the can is obtained by annularly severing the side wall of any desired section.

In the form of invention shown in Figures 14 to 16, the can is formed of sections 58 with the adjacent edges of the can sections associated with a partition 59 in the form of a plate or disk that carries a depending annular skirt 60 that is annularly grooved inwardly as at 61. As shown in Figure 16, the skirt 60 at opposite sides of the groove 61 slightly bulge outwardly to provide a more intimate contact with the inner faces of the adjacent ends of the can sections 58. A relatively thin layer of solder or other sealing material 62 hermetically seals the adjacent ends of the can sections to the annular skirt 60 of the partition wall 59. To open the can for access to the compartment, the annular skirt 60 is severed through the channel portion 61 thereof and the partition wall 59 constitutes a bottom wall for the superposed section or compartment of the can. It is to be understood that the can may be formed of any number of sections or compartments desired.

Another form of can seam in a compartment can with the marginal edge of the partition embedded in the seam is illustrated in Figures 17 and 18, the adjacent ends of the can sections 63 and 64 respectively carrying interfitting flanges 65 and 66 V-shaped in cross-section, the flange 65 being located at the inner side and receiving in its apex a marginal edge of the partition 67. The flanges 65 and 66 with the marginal edge of the partition are moved into L-formation as shown at 68 in Figure 18 with the marginal edge of the partition being directly engaged with the flanges 65 and 66, the flange 66 being bent upwardly, inwardly and downwardly at 68a to enclose the outwardly and downwardly bent flange 65 of the upper section 63 of the can.

The can seam shown in Figures 19 to 21 is similar to the can seam shown in Figures 17 and 18 with the can sections 63a and 64a carrying at their adjacent ends flanges 69 and 70 that are V-shaped in cross-section with the marginal

edge of the partition 71 extending into the apex of the inwardly positioned V-shaped flange 69. Figure 20 shows the initial compression imparted to the interfitting flanges and marginal edge of the partition and Figure 21 shows the flanges bent into L-formation as at 72, it being noted that the flange 69 engaged with the upper side of the partition 71 and is extended around the upwardly bent marginal edge of the partition and then directed inwardly as at 73 to underlie the marginal edge of the partition and to be interposed between the partition and lower flange 70, thereby adding additional surface contact to the walls of the seam for the more effective sealing of the joints.

In the form of invention illustrated in Figures 22 to 24, the can body 74 has its cylindrical side wall of one piece construction that is annularly bulged outwardly as at 75 at spaced points for the reception of partitions 76 that has a marginal upstanding bead 77 and a depending skirt 78. The sections of the can formed by the bulged portions 75 may be of slightly less diameter in a downward direction to cause the lower edge of the skirt 78 of the partition 76 to enter the bulged portion and be prevented from further downward movement. The subsequent compression of the side walls of the bulged portion 75 causing the skirt 78 to be moved outwardly into the bulged portion to assume the positions shown in Figure 24 and at the lower partition in Figure 22, the bulged portion 75 then being moved into L-formation in cross-section as shown at 75a to facilitate guiding movement of a can opener employed therewith.

In each form of the invention disclosed herein, the partitions provide non-communicating compartments so that foods of different kinds to constitute a complete dinner or meal may be carried in a single can. It is also possible to obtain access to any one of the compartments of the can with the remaining compartments remaining in a hermetically sealed condition and while there are herein shown and described the preferred embodiments of the invention, it is nevertheless to be understood that minor changes may be made therein without departing from the spirit and scope of the invention as claimed.

I claim:

In a compartment can for packaging foods, 50 a tubular can body having diametrically opposite curved walls and intervening flattened wall portions extending longitudinally of the can, partitions in the can body dividing the same into non-communicating compartments, the marginal 55 edges of the partitions having sealing engagement with the can body and relatively shiftable in the can body for varying the relative areas of the compartments, a weakened tearing line at each point of emergence of the flattened and 60 curved wall portions of the can and a tongue extension on opposite ends of the respective flattened portions normally extending over the adjacent end of the can whereby a key may be employed for tearing and rolling a flattened portion 65 from either end of the can for exposure of the compartment.

EDWARD HOLOUBEK.
